MINING MACHINE AND ELEMENTS THEREOF

Frank L. Fulke, Terre Haute, Ind., assignor to
 Frank Prox Company, Terre Haute, Ind., a corporation of Indiana

Application May 27, 1935, Serial No. 23,592

9 Claims. (Cl. 262—33)

The present application relates to mining machine cutter chains and the elements thereof, particularly the links themselves, the manner of associating bit-gripping devices with such links, and means for associating cutter bits with such devices.

Mining machine cutter chains are made up of a plurality of individual links, at least some of said links carrying, in some suitable manner, cutter bits adapted to attack the coal into which the chain is fed by bodily movement of the mining machine or the cutter bar thereof. In the practical mining machine art, it has been almost, if not quite, universal practice to use, with such links, cutter bits having long integral shanks extending into sockets formed in the chain links, and secured therein in some suitable manner. Within the past few years, that practice has been invaded, to some extent, by the introduction of relatively small bits, sometimes reversible, held in place between clamping members suitably carried in or on the chain links. It is an object of the present invention to provide, for use with a small double-pointed bit, clamping means of novel characteristics which shall be more effective in holding the cutter bits, more readily manipulable to permit substitution or reversal of such cutter bits, and more reliable in operation than any of such clamping means heretofore introduced to the practical art.

Further objects of the invention will appear as the description proceeds.

To the accomplishment of the above and related objects, my invention may be embodied in the forms illustrated in the accompanying drawings, attention being called to the fact, however, that the drawings are illustrative only, and that change may be made in the specific constructions illustrated and described, or in the specific steps stated, so long as the scope of the appended claims is not violated.

Fig. 1 is a side elevation of a mining machine chain link having associated therewith novel clamping means for supporting upon the link a suitable double-pointed bit, said clamping means and bit being constructed in accordance with the present invention, and parts being broken away for clarity of illustration;

Fig. 2 is a plan view thereof;

Fig. 3 is a longitudinal section through another form of clamping mechanism constructed in accordance with the present invention;

Fig. 4 is a horizontal section through the same, looking upwardly;

Fig. 5 is a side elevation of a tooth or bit which

I have invented and which is illustrated in association with various clamping means of the present application;

Fig. 6 is a rear elevation thereof;

Fig. 7 is a top plan view thereof;

Fig. 8 is a front elevation, upon an enlarged scale, of one element of the clamping means of Fig. 3;

Fig. 9 is a diagrammatic view illustrating the manner of producing the element of Fig. 8;

Fig. 10 is a view similar to Fig. 3, but showing a further form of clamping mechanism;

Fig. 11 is an end elevation thereof;

Fig. 12 is a section taken on the line 12—12 of Fig. 10, and looking in the direction of the arrows;

Fig. 13 is a view similar to Fig. 3 but showing a further modification; and

Fig. 14 is a view similar to Fig. 3 and showing a still further modification.

Referring, first, to the form of the invention illustrated in Figs. 1 and 2, it will be seen that I have shown a more or less conventional mining chain link indicated generally at 20, and comprising a body portion 21, a head 22, and terminal ears 23, 23, said ears being provided with perforations 24, 24 for the reception of rivets connecting said link in the chain. While I have illustrated a link in which the head 22 is centrally located, it will be recognized that the invention is applicable to links in which the head is offset; and, as the description of the link of Figs. 1 and 2 continues, it will be perceived that such link is reversible, so that two identical links may be reversely located in a chain to position the offset heads thereof respectively to one side and the other side of the median plane of the chain.

The link 20 is formed with a rectangular broached opening 25 extending completely therethrough, from the upper surface of the head 22 to the bottom of the body portion 21; and in said opening 25 is received clamping mechanism for holding a bit in position on the link to attack the coal into which the chain is fed by bodily movement of the mining machine, or the cutter bar thereof.

The clamping or gripping mechanism illustrated in Fig. 1 comprises a plurality of members including a wedge member 26 of generally rectangular cross section and provided with a rearwardly and upwardly presented wedge face 27. At its forward face, said wedge member 26 is formed with at least one transverse groove; and I prefer to form at least three of such grooves, 28,

29, and 30, vertically spaced from each other. The front wall of the opening 25 is formed with a groove 31, and it will readily be seen that a pin 32 is adapted to be received in the groove 31 and 5 in one of the grooves 28, 29, or 30 to hold the wedge member 26 rigidly in place in the opening 25.

The purpose of providing a plurality of grooves 28, 29, and 30 in the wedge member 26 is to permit variation in the gage of the cutter bit, with 10 respect to the link 20.

The clamping mechanism comprises also a jaw element 33 formed, in its forward face, with a groove comprising a seating section 34, which has 15 the shape of a segment of a double-convex disc, and a portion 35, the flaring walls of which have the shape of the walls of the portion 34, but the base of which is not curved.

The portion 35 of said groove merges into a 20 socket 36 terminating at its lower end in a shoulder 37. The lower end of the element 26 is formed likewise with a socket 38 which is open at its lower end; and a coiled spring 39 is received in said sockets 36 and 37, bearing at its upper 25 end against the end of the socket 38, and at its lower end against the shoulder 37.

A cutter bit 40 is received between the groove 34 and the wedge surface 27 of the element 26. It will be seen that, since the element 26 is rigidly held by the pin 32, the tendency of the spring 39 is to force the element 33 downwardly to clamp the cutter bit 40 tightly between the cam surface 27 and the jaw groove 34.

The bit 40 is of unique construction, fitting 35 closely within the groove 34, with its lower end within the portion 35 of the groove in the element 33, but free from abutment against anything. It will be seen that the bit 40 is held by the engagement of the element 33 and 26 with portions of 40 said bit intermediate its ends. The exact construction of the bit 40 will be described hereinafter.

Adjacent its upper ends, the element 33 is 45 formed with a socket 41 into which is adapted to be inserted a pin 43 carried by a tool 42. Said tool carries also a pin 44 adapted to engage the top surface of the link head 22; so that clockwise movement of the tool 42 will act to lift the element 33 against the tendency of the spring 39 to release the bit 40.

50 Referring now to the embodiment of my invention illustrated in Figs. 3 and 4, it will be seen that the link head 45 is formed with a pair of sockets 46 and 47 of circular cross section, said sockets being bored on parallel axes, and such axes being spaced apart a distance somewhat less than the sum of the radii of said respective bores, whereby said sockets overlap to provide communication therebetween throughout their 60 lengths.

In the socket 46 is received a jaw element 48 formed, in its forward face, with a groove comprising a seating section 49 which has the shape of a segment of a double-convex disc, and a portion 50, the walls of which have the shape of the walls of the portion 49, but which is not curved. Adjacent its upper end, the element 48 carries a rearwardly projecting pin 51; and adjacent its lower end, said element 48 carries a forwardly 70 projecting pin 52.

The socket 47 receives a wedge element 53 formed with an upwardly and rearwardly facing wedge surface 54 adjacent its upper end. Adjacent its lower end, said element 53 is formed with 75 a socket 55 opening through the lower end of

said element, said socket receiving a coiled spring 56. The rear wall of said element 53 is provided, adjacent its lower end, with a slot 57 through which the pin 52 projects into engagement with the lower end of spring 56. The front wall of the element 53 is formed with a transverse groove 58 adapted to register with a transverse groove 59 formed in the head 45. A pin 60 is adapted to be received, partially in the groove 58 and partially in the groove 59, to hold said element 53 rigidly in place in its socket 47; and it will be quite clear that the spring 56, bearing on the pin 52, tends to hold the element 48 downwardly in its socket 46.

A cutter bit 40, identical with the bit 40 of Fig. 1, is snugly received in the seating portion 49 of the groove of the jaw element 48 and is engaged, on its flat front face, by the wedge face 54 of the element 53. Obviously, the tendency of the spring 56 is to wedge the bit 40 tightly in place between 20 the seat 49 and the surface 54.

For manipulating the element 48, I prefer to provide a tool having a head 61 in which is eccentrically formed an aperture 62 adapted to receive the pin 51. Said tool comprises also a shank 63; and it will be obvious that, when the tool is associated with the pin 51 in the manner indicated in Fig. 3, rotative movement of the shank 63 in either direction will bring the cam head 61 into contact with the link head 45 to lift 30 the element 48 against the tendency of the spring 56, thereby releasing the bit 40.

In Fig. 9, I have illustrated diagrammatically the manner of forming the groove 49—50 in the element 48. The cutter indicated generally at 64 35 comprises a plurality of teeth 65, the outer end of each of which has substantially the form of a Gothic arch, said teeth being mounted upon a rotatable shaft 66. It will be clear that suitable 40 operation of the cutter 64 will form the straight-backed portion 50 and the curved portion 49 of said groove. This same operation is used in forming the groove in the jaw member of each of the clamping assemblies illustrated in the present application.

In Figs. 5, 6, and 7, I have illustrated in detail 45 the bit or tooth which I prefer to use with my gripping devices. Said bit comprises a flat front wall 67, the contour of which is a sharp-ended ellipse; and two identical-convex walls 68 and 69, the contours of which are segments of convex circular figures. The walls 68 and 69 meet in a relatively sharp curved edge 70; the walls 67 and 68 meet in a curved cutting edge 71; and the walls 67 and 69 meet in a curved cutting edge 72, identical with the edge 71. The edges 71 and 72 meet, in the plane of the edge 70, in a sharp cutting point 73, at one end, and in a sharp cutting point 74, at the other end.

Briefly stated, the completed bit has the shape 60 of a minor segment of a disc which diminishes in thickness, in a curved line, toward its edge; in other words, a minor segment of a double-convex disc.

In Figs. 10 to 14 I have illustrated three other 65 forms of clamping means. Figs. 10 to 12 inclusive illustrate a form in which the head 116 of a link 115 is formed with a pair of paraxial sockets 117 and 118. A jaw member 119 is received in the socket 117, and is formed in its forward face with a groove having a seating section 120 of the above-described characteristics 70 and a lower section 121. A wedge member 122, having an upwardly and rearwardly presented wedge face 123, is received in the socket 118, and 75

is provided with a reduced threaded extension 124 threadedly received in a threaded socket 125 at the base of the socket 122.

Adjacent its lower end, and in its rear face, the element 119 is notched to provide a shoulder 126 against which bears one end of a spring 127 received in a socket 128 formed in the head 116 at an angle to the socket 117, and communicating therewith. The other end of the spring 127 bears against an adjustable abutment 129 threaded into the outer end of the socket 128.

Adjacent its upper end, the element 119 carries a rearwardly projecting pin 130 with which may be associated a manipulating tool 131 provided with an eccentrically formed aperture 132 adapted to receive said pin 130. The manner of manipulation of the element 119 is identical with the manner of manipulation of the element 48.

In Fig. 13, I have shown a link 133 having a head 134 provided with paraxial sockets 135 and 136. The socket 135 slidably receives a jaw element 137 formed with a groove having a seating portion 138 and a straight portion 139. A wedge member 140 having an upwardly and rearwardly presented wedge face 141 is received in the socket 136 and is formed, in its forward face, with a pocket 142 receiving the reduced end 143 of a screw 144 threadedly mounted in a threaded bore 145 communicating with the socket 136. Obviously, the screw 144 will hold the element 140 against movement in its socket 136.

The head 134 is formed, adjacent the socket 135, with a paraxial, internally threaded socket 146 receiving an adjusting screw 147 provided with an annular flange 148 received in a notch 149 in the rear face of the element 137. Obviously, rotation of the screw 147 in one direction or the other will move said screw upwardly or downwardly; and the element 137 will participate in any such reciprocating movement of the screw 147.

In Fig. 14 I have shown a link 150 having a head 151 provided with paraxial sockets 152 and 153. A jaw element 154 is received in the socket 152 and is formed in its front face with a groove comprising a seating section 155 and a straight section 156. A wedging element 157, having an upwardly and rearwardly presented wedge face 158, is received in the socket 153, said element 157 being provided with a reduced threaded extension 159 received in a threaded socket 160 at the base of the socket 153. In its rear face, the element 154 is provided with a laterally elongated slot 161 adapted to receive an eccentric projection 162 on an element 163 rotatably mounted in the head 151. As shown, said element 163 comprises a threaded portion 164 received in a threaded bore 165 in the head 151; but it will be clear that said element 163 might be a smooth-sided element received in a smooth bore, there being means provided for preventing axial movement of said element, and for holding said element against accidental rotation.

It will be seen that all of the clamping mechanisms illustrated in the present application show, as a common characteristic, the idea of the provision of two cooperating clamping elements, one being held against movement, and the other being movable axially to clamp the bit between said elements. This characteristic permits the arrangement in which the transverse dimensions of the clamping elements snugly fit the sockets in which said elements are received; and in this respect, all of the clamping mechanisms illustrated herein differ from prior

art clamping mechanisms known to me. In all of the clamping mechanisms of the patented art and the practical art, of which I have knowledge, the movement of the movable element of the clamping mechanism has been either in a direction generally transverse to the axis of the associated clamping element, or has been a rocking movement about an axis transverse to the axis of the clamping elements. Either of these arrangements requires clearances which, in use, rapidly become clogged with coal dust; thereby interfering with, if not completely destroying, the operability of the clamping mechanism. As is clearly to be seen from an inspection of the drawings of the present application, there is nowhere, in any one of the clamping mechanisms illustrated herein, any room for coal dust to enter and clog any portion of the clamping mechanism.

It will be seen that the association of my immovable wedging element, my yieldable seating element, and my bit embraced between them is such that a very powerful wedgelock is established, and it will also be apparent that working forces received by the bit while the cutting operation progresses will aid and urge this wedge-locked relationship of these associated parts toward greater solidity and security.

I claim as my invention:

1. A mining chain link, a pair of bit supporting elements associating a bit with said link, a bit engaged by and between said supporting elements, a spring between and engaging said elements and biasing the bit-engaging portions of said elements toward each other.

2. A mining chain link having a socket, a bit and a pair of bit supporting elements in said socket, one of said elements being urged inwardly of said socket by a spring engaged between said bit-supporting elements, an unlocking device engaging said element and said link and operable to shift said one element in an outward direction against said spring influence.

3. The combination with a mining machine chain link, of a cutter bit and means carried by said link for holding said bit, said means comprising a jaw member formed to provide a seat having a pair of converging walls meeting in a curved line lying in a plane between said walls, said seat snugly receiving said bit, a wedge member associated with said jaw and adapted to engage a surface of said bit, and means for shifting one of said members relative to the other to clamp said bit between said wedge member and said seat.

4. The combination with a mining machine chain link having a socket therein, of a cutter bit and means received in said socket for holding said cutter bit, said means comprising a wedge member received in said socket, means for holding said wedge member in place in said socket, a jaw member received in said socket, said wedge member and said jaw member being formed with cooperating seating surfaces for clamping said bit therebetween, and spring means urging said jaw member in a clamping direction.

5. The combination with a mining machine chain link of a plural-pointed bit, and cooperative members engageable with said bit for locking the same in place on said link, one of said members being threadedly attached to said link, whereby optional gauge between the bit point and the link may be obtained.

6. The combination with a mining machine chain link having formed therein two paraxial part-cylindrical sockets, the distance between the

axes of said sockets being greater than the radius of either of said sockets, but less than the sum of the respective radii of said sockets, of a cutter bit, and means received in said sockets for holding said cutter bit.

7. The combination with a mining machine chain link having a socket therein, of a cutter bit and means received in said socket for holding said cutter bit, said means comprising a wedge member received in said socket, a jaw member received in said socket, said wedge member and said jaw member being formed with cooperating seating surfaces for clamping said bit therebetween, an element rotatably mounted in said link on an axis substantially perpendicular to the axis of said socket, said jaw member being formed with a slot, and an eccentric projection on said element received in said slot, whereby rotation of said element shifts said jaw member axially in its socket.

8. The combination with a mining machine chain link having formed therein two paraxial part-cylindrical sockets, the distance between the axes of said sockets being greater than the radius of either of said sockets but less than the sum of the respective radii of said sockets, of a cutter bit, an element secured in one of said

sockets, a clamping element slidably received in the other of said sockets, said elements being formed with cooperating surfaces clampingly receiving said bit therebetween, said clamping element being formed with a step disposed in a plane intersecting the line of movement of said clamping element, and a member received in said link and movable in a line substantially perpendicular to the plane of said step and engaging said step to urge said clamping element into clamping engagement with said bit.

9. In combination, a mining machine chain link formed to provide two intersecting paraxial part-cylindrical sockets, a clamping element slidably mounted in one of said sockets, a cutter bit, means removably mounted in the other of said sockets and providing a surface cooperative with a surface on said clamping element for clampingly engaging said bit, a step formed on said clamping element and disposed in a plane angularly intersecting the axis of movement of said clamping element, and a member carried by said link and movable in a line substantially perpendicular to said plane and engaging said step to urge said clamping element into clamping engagement with said bit.

FRANK L. FULKE.
